UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAYBOLT STRUCTURE.

1,380,541.

Specification of Letters Patent. Patented June 7, 1921.

Application filed January 20, 1920. Serial No. 352,692.

To all whom it may concern:

Be it known that I, ETHAN I. DODDS, a citizen of the United States, and a resident of Pittsburgh, in the county of Allegheny and State of Pennsylvania, have invented 5 certain new and useful Improvements in Staybolt Structures; and I do hereby declare the following to be a full, clear, and exact description of the invention, such as will 10 enable others skilled in the art to which it appertains to make and use the same.

This invention relates to improvements in staybolt structures for boilers and more particularly to means affording a mounting for 15 the headed outer end of a staybolt and its connection with a boiler sheet,—objects of the invention being to so construct a two-part structure comprising a bearing member and a closure member, that said structure 20 shall be capable of universal adjustment in the opening in the boiler sheet; so that one or both members may be seated against the boiler sheet; to weld a bearing structure to the boiler sheet in such manner as to confine 25 the weld to a limited surface of the structure to facilitate removal of said structure from its welded union with the boiler sheet when removal of a broken bolt is necessary, and to so construct the device that it may be mounted 30 with its outer end substantially flush with the outer face of the outer boiler sheet or made to project outwardly beyond the same.

With these and other objects in view, the 35 invention consists in certain novel features of construction and combinations of parts as hereinafter set forth and pointed out in the claims.

In the accompanying drawings; Figure 1 40 is a sectional view, partly in elevation, showing an embodiment of my invention; Fig. 2 is a view showing the manner of connecting the device with the boiler when a structure of the "flush" type is desired, and Figs. 3 45 and 4 are views illustrating a modification.

1 represents an outer boiler sheet and 2 the inner sheet of a boiler.

A staybolt 3 is secured in any suitable manner to the inner boiler sheet, and said 50 staybolt is provided at its outer end with a head 4 which is connected with the outer boiler sheet as hereinafter described.

The outer boiler sheet 1 is provided with an opening 5, the major portion of the wall 55 of which is rounded transversely of the sheet

to provide a rounded seat 6 which may extend from the outer face of the sheet approximately to the inner face. This seat receives a two-part mounting for connecting the head of the bolt with the boiler sheet, 60 said mounting comprising a bearing member 7 and a closure member 8,—the bearing member having an internal rounded seat 9 for the head of the bolt, an exterior rounded portion 10 mounted on the rounded seat 6 in 65 the boiler sheet, and an externally threaded portion 11 which enters an internally threaded portion of the closure member. The closure member 8 is made with a rounded exterior portion 12 in the same arc as the 70 rounded portion 10 of the bearing member and is mounted on the rounded seat 6 in the boiler sheet. Thus it will be seen that both the bearing member 7 and the closure member 75 have universally adjustable mounting in the opening in the boiler sheet to insure proper alignment of the staybolt with its points of connection with the respective boiler sheets.

The closure member 8 is made with a circumferential groove 13 located in that portion of said member which projects beyond the boiler sheet when mounted as shown in Fig. 1. The groove 13 may contain a gasket 14 made of a material with which a welding 80 alloy will not cohere,—such for example, as mineral wool or clay. A weld 15 surrounds the projecting portion of the closure member and the gasket 14 and unites said closure member to the boiler sheet. By the provision 85 of the groove containing a material to which the welding alloy will not cohere, the extent of surface of the closure member with which the weld coheres will be restricted and hence the difficulty of chiseling off the 90 weld will be reduced and the withdrawal of the structure to remove a broken bolt will be facilitated. If desired, the gasket 14 may be omitted, and the welding alloy prevented 95 from filling the groove.

The closure member may be provided with a flange 16 at its outer end which, in the "flush" mounting shown in Fig. 2 lies within the opening in the boiler sheet, and the edge of this flange may be beveled as 105 shown at 17.

The opening in the boiler sheet (in Fig. 2) is made with a rounded wall forming a seat 18 extending from the inner face of the sheet approximately to the outer face, and on 110

which the rounded closure member has a universally movable mounting. The outer portion of the wall of the opening in the boiler sheet may be beveled, as at 19, and this 5 beveled wall forms, with the beveled edge 17 of the flange 16, a groove which is occupied by a weld 20 whereby the structure, when mounted as shown in Fig. 2, is welded to the boiler sheet. Should it be necessary to 10 move a broken bolt, the mounting may be released by cutting off the flange 16 with the use of a suitable tool or tools.

In the embodiment of the invention shown 15 in Figs. 3 and 4, 1^a represents the outer sheet of a boiler and 2^a the inner sheet. A staybolt 3^a is secured at its inner end, in any suitable manner, to the inner boiler sheet 2^a and said staybolt is provided at its outer end with a head 4^a which is connected with the 20 outer boiler sheet 1^a as hereinafter explained.

When the device is employed as a "flush" structure, as shown in Fig. 3, the outer boiler sheet is provided with a conical opening 5^a to receive a closure member 6^a having 25 a conical exterior. The closure member 6^a is hollow and is made in a single piece, its inner end being open and its outer end being closed, and the said outer end presenting a face 7^a which lies flush with the outer face 30 of the boiler sheet 1^a. The peripheral portion of the bearing member is beveled at the outer end of the latter, as at 8^a, and this beveled portion forms, with a portion of the wall of the opening in the boiler sheet, a 35 groove in which a weld 9^a is located,—said weld fixedly uniting the bearing member to the boiler sheet.

The hollow closure member 6^a is made 40 interiorly with a threaded wall 10^a and receives the threaded exterior of a bearing sleeve 11^a, the upper end of the latter abutting against a shoulder 12^a in the bearing member and its lower end terminating at the inner open end of said bearing member. 45 A portion of the interior of the bearing sleeve is rounded to provide a seat 13^a for the rounded head of the staybolt and the inner portion of the opening in the bearing sleeve may be made flaring, as at 14^a, to provide for 50 the swing of the staybolt.

The closure member is made with a concave interior portion 15^a to provide a clearance space 16^a for the bolt head.

If desired my improved structure may be 55 mounted on the outer face of the boiler sheet 1^a and united thereto by a weld 17^a,—in which case, the opening 5^a in the boiler sheet may be made cylindrical and appreciably greater in diameter than the diameter of the 60 staybolt, as shown in Fig. 4.

Having fully described my invention what I claim as new and desire to secure by Letters-Patent, is:—

1. In a staybolt structure, the combination 65 with a boiler sheet having an opening,

of a closure member permanently closed at its outer end and threaded interiorly, said closure member initially seated freely against the boiler sheet approximately in line with the opening therein, a bearing 70 member threaded in said closure member and having an interior seat, a staybolt having a head mounted on the seat in said bearing member, and a weld uniting said closure member to the boiler sheet. 75

2. In a staybolt structure, the combination with a boiler sheet having an opening, of a closure member, and a bearing member threaded therein and both adapted to be seated simultaneously against the boiler 80 sheet approximately in line with the opening therein, a weld uniting said closure member to the boiler sheet, and a staybolt having a head mounted in said bearing member. 85

3. A mounting for a staybolt, comprising a bearing member for the head of a staybolt and a closure member having removable connection with the bearing member, said closure member provided with an annular 90 flange, the metal effecting the union of said flange with the body of the closure member being comparatively thin whereby said flange may be removed, said flange having a beveled edge portion to be welded to a 95 boiler sheet inwardly of the outer face thereof.

4. In a staybolt structure, the combination with a boiler sheet having an opening, of a mounting for a staybolt, a staybolt having a head seated in said mounting, said mounting having a groove around the same, and a weld surrounding said mounting and uniting the same to the boiler sheet, said weld overlying the groove in the mounting 100 whereby said weld will have a restricted cohesive union with the metal of the mounting. 105

5. In a staybolt structure, the combination with a boiler sheet having an opening, 110 of a mounting for a staybolt, a staybolt having a head seated in said mounting, said mounting having a groove around the same, material in said groove, and a welding alloy surrounding the mounting and overlying 115 said material and to which the welding alloy will not cohere and a restricted portion of the metal of the mounting, said welding alloy uniting the mounting to the boiler sheet. 120

6. In a staybolt structure, the combination with a boiler sheet having an opening, of a bearing device having a rounded exterior and initially universally adjustable in said opening, said bearing device having 125 a circumferential recessed portion, a gasket in said recessed portion, a staybolt provided with a head mounted in said bearing device, and a welding alloy overlying said gasket and to which latter the welding alloy 130

will not cohere, said welding alloy uniting the bearing device to the boiler sheet.

7. In a staybolt structure, the combination with a boiler sheet having an opening, 5 of a bearing device mounted in said opening and projecting outwardly beyond the boiler sheet, said bearing device having a circumferential recessed portion, a gasket in said recessed portion, a welding alloy surrounding the bearing device in engagement with the gasket without cohesion and overlying a portion of the bearing device, said welding alloy uniting the bearing device to the boiler sheet, a staybolt provided with a head 10 mounted in said bearing device, and a portion of said bearing device constituting a removable closure over the bolt head.

8. A bearing device approximately hemispherical in outline and having a welding 20 flange at its outer end and a circumferential recess, said bearing device including two members having threaded connection with each other and one of said members having

a seat for the head of a staybolt, and a gasket in said recess of material to which 25 a welding alloy will not cohere, one member of said device constituting a threaded closure.

9. A mounting for a staybolt provided with a seat for the head of a staybolt, said 30 mounting having a circumferential groove, and a gasket in said groove, said gasket being of material to which a welding alloy will not cohere.

10. A mounting for a staybolt comprising 35 a closure member and a bearing member having threaded connection with said closure member and provided with a seat for the head of a staybolt, said closure member having a circumferential groove and said 40 closure member also having an annular flange at its outer end portion.

In testimony whereof, I have signed this specification.

ETHAN I. DODDS.
